UNITED STATES PATENT OFFICE.

EPPA H. RYON, OF WALTHAM, MASSACHUSETTS, ASSIGNOR TO CROMPTON & KNOWLES LOOM WORKS, OF WORCESTER, MASSACHUSETTS, A CORPORATION OF MASSACHUSETTS.

WARP STOP-MOTION.

1,268,159.

Specification of Letters Patent.

Patented June 4, 1918.

Application filed July 2, 1917. Serial No. 178,114.

To all whom it may concern:

Be it known that I, EPPA H. RYON, a citizen of the United States, residing at Waltham, in the county of Middlesex and State 5 of Massachusetts, have invented a new and useful Warp Stop-Motion, of which the following is a specification.

This invention relates to a warp stop motion of the mechanical type.

10 It is the general object of my invention to provide a warp stop motion of this type in which power-actuated devices are provided for engaging and drawing downward a fallen drop wire, thus rendering operative the loom stopping mechanism controlled thereby.

15 In the preferred form said devices comprise a pair of parallel horizontal rollers positioned adjacent each other and beneath the drop wires, said rollers being continuously rotated through suitable driving connections.

An important feature of my invention relates to the provision of a depressible indicating bar for each bank of drop wires, 25 movable downwardly whenever any one of the wires is engaged by said rollers, and connections by which the loom stopping mechanism is rendered operative through downward movement of said indicating bars or 30 any one of them.

Another feature of my invention relates to the provision of drop wires which are roughened or toothed at their lower ends, thereby increasing the effectiveness of the rollers.

35 Further features of my invention relate to arrangements and combinations of parts which will be hereinafter described and more particularly pointed out in the appended claims.

40 A preferred form of my invention is shown in the drawings, in which—

Figure 1 is a front elevation of my improved stop motion;

Fig. 2 is a right-hand side elevation of the 45 parts shown in Fig. 1;

Fig. 3 is a partial plan view of the stop motion;

Fig. 4 is a diagrammatic view showing the 50 operation of the stop motion, and

Fig. 5 is a view of a modified form of drop wire.

Referring to the drawings, my improved stop motion is supported by end frames 10 and 11 adjustable in the direction of the 55 warp threads upon L-shaped rods 12 which

in turn are adjustable transversely of the warp threads in supports 13. These supports are vertically adjustable in brackets 14 secured to the loom sides 15.

The end frames 10 and 11 are connected by 60 side bars 16 and 17, these side bars inclosing the drop wires. The separate banks of wires are kept apart by light rods 18 secured to the end frames 10 and 11 by screws 19. While only two banks of wires are shown in 65 the drawings, it will be understood that the capacity of the stop motion can be increased by spacing the side bars 16 and 17 farther apart and providing additional separator wires 18.

The frame 10 supports a bearing stud 20 on which is pivotally mounted a bell crank 21. A link 22 is pivoted on a stud 23 secured in the upstanding arm 24 of the bell crank 21, and a rod 25 pivoted to the outer end of 70 the long arm of the bell crank 21 is connected to control loom stopping mechanism not shown. The end frame 10 is provided with an upwardly extending arm 30 to which a link 31 is pivoted by a stud 32. Detachable 75 indicating bars 33 and 34 (Figs. 1 and 3) are supported on studs 35 and 36 fixed in the ends of the links 22 and 31 respectively. The ends of the bars are so formed that the bars may be readily removed upwardly when so 80 desired, the outline of these connections being shown in dotted lines in Fig. 1. A separate indicating bar is of course provided for 85 each bank of drop wires.

The weight of the bell crank 21, rod 25 90 and the parts connected thereto are such that the bars 33 and 34 are normally maintained in the position shown in Fig. 1, or in the position of the bar 33 in Fig. 4.

The frames 10 and 11 are extended downwardly to form open-sided bearings 40 for a roller 41 rotatably mounted therein. A swinging arm 42 is pivoted to each frame 10 and 11 and is moved yielding toward the roller 40 by a spring 43. At their lower ends 95 the arms 42 are provided with open-sided bearings for a second roller 44 extending parallel and adjacent the roller 41. Intermeshing gears 45 carried by the rollers 41 and 44 insure simultaneous and opposite rotation of the rolls. The roll 41 may be actuated by any suitable driving mechanism and is shown in the drawings as provided with a pulley 46 driven by a belt 47 from the bottom shaft of the loom (not shown). 100 105 110

The rolls 41 and 44 are preferably formed with resilient or yielding outer surfaces 48, as shown in Fig. 4, and it is also desirable but not absolutely essential that the portions 5 48 should be provided with intermeshing corrugations as also shown in Fig. 4.

When the stop motion is in use the bars 33 and 34 extend through slots 50 in the upper ends of drop wires 51, the lower ends 10 of the wires preferably having open-ended slots 52 by which they are supported upon the warp threads.

The operation of my improved stop motion is exceedingly simple. Whenever a 15 warp thread breaks the corresponding drop wire falls from the position shown at the left in Fig. 4 to a position in which the lower end of the drop wire is engaged by the rotating rollers 41 and 44. Such engagement 20 draws the drop wire downward between the rollers, carrying with it the bar 33 or 34, extending therethrough, and thus moving the bell crank 21 upon its pivot 20 to raise the rod 25 and thus stop the loom. When 25 the drop wire has been drawn downward to its limit of travel the resilient surfaces of the rollers and the springs 43 yield sufficiently to permit the continued rotation of the rollers.

30 Under some conditions I have found that it is desirable to roughen the lower end of the drop wire in some manner as by providing teeth 53 (Fig. 5) at the lower end of the wire. When thus formed the wire is 35 somewhat more strongly drawn downward by the rollers 41 and 44.

It will thus appear that I have invented an exceedingly simple stop motion which is 40 entirely lacking in delicate parts and which does not require a careful adjustment of balanced springs to insure successful operation.

Having thus described my invention, it 45 will be evident that changes and modifications can be made therein by those skilled in the art without departing from the spirit and scope of my invention as set forth in the claims, and I do not wish to be otherwise limited to the details herein disclosed, 50 but what I do claim is:—

1. A warp stop motion comprising drop wires, an indicating bar for each bank of drop wires, depressible by downward movement of any one of said drop wires, devices 55 mounted beneath said drop wires effective to engage and draw downward a fallen drop wire, and loom stopping mechanism controlled through said indicating bar, said devices being effective through 60 said fallen drop wire to draw downward said indicating bar and thereby render said loom stopping mechanism operative.

2. A warp stop motion having, in combination, drop wires, each having an opening 65 therein, an indicating bar extending

through said openings, loom stopping mechanism controlled through said indicating bar, and power-actuated mechanical devices effective to engage and pull a fallen drop wire downward and thereby depress 70 said indicating bar and thus render said loom stopping mechanism operative.

3. A warp stop motion comprising drop wires, a movable indicating bar for each bank of drop wires, depressible by downward movement of any one of said drop wires, power-actuated devices effective to draw downward a fallen drop wire, thereby 75 directly depressing said indicating bar, and loom stopping devices controlled through 80 said indicating bar.

4. A warp stop motion comprising drop wires, depressible indicating devices associated with said drop wires, a pair of rollers mounted beneath said drop wires, 85 means to actuate said rollers to engage and draw downward a fallen drop wire, thereby depressing said devices, and loom stopping mechanism controlled by said devices.

5. A warp stop motion comprising a bank 90 of drop wires, a depressible indicating bar for said drop wires, a pair of rollers mounted beneath said drop wires and effective to engage and draw downward a fallen drop wire, thereby depressing said bar, 95 means to rotate said rollers continuously, and loom stopping devices controlled through said indicating bar.

6. A warp stop motion comprising a frame, a bank of drop wires, a link 100 mounted on a fixed support at one end of said frame, a bell crank pivoted at the other end of said frame, a second link connected to said bell crank, rods connecting said links, said rods extending through slots in 105 said drop wires, a pair of rollers rotatably mounted in said frame beneath said drop wires, means to rotate said rollers continuously, and loom stopping mechanism controlled through said bell crank.

7. A warp stop motion comprising a frame, a bank of drop wires, a link mounted on a fixed support at one end of said frame, a bell crank pivoted at the other end of said frame, a second link connected to said bell 110 crank, rods connecting said links and detachably secured thereto, said rods extending through slots in said drop wires, a pair of rollers rotatably mounted in said frame beneath said drop wires and each having a yielding resilient covering, means to rotate said rollers continuously, and loom stopping mechanism controlled through said bell crank.

8. A warp stop motion comprising a bank 115 of drop wires, a depressible indicating bar for said drop wires, a pair of rollers mounted beneath said drop wires, means to actuate said rollers to engage and draw 120 downward a fallen drop wire, thereby de- 130

pressing said bar, and loom stopping devices controlled by said bar, said rollers being formed of resilient material and being corrugated longitudinally.

5. A warp stop motion comprising a bank of drop wires, a depressible indicating bar for said drop wires, a pair of rollers mounted beneath said drop wires, means to 10 actuate said rollers to engage and draw downward a fallen drop wire, thereby depressing said bar, and loom stopping devices controlled by said bar, said rollers being formed of resilient material and being mounted for yielding movement toward and 15 from each other.

10. A warp stop motion comprising drop wires, a depressible indicating bar for each bank of drop wires, a pair of rollers mounted beneath said drop wires, means to 20 actuate said rollers to engage and draw

downward a fallen drop wire, thereby depressing the associated indicating bar, and loom stopping devices controlled by said bar, said drop wires having their lower ends roughened, whereby said rollers may exert 25 a stronger pull upon said wires and indicating bar.

11. A warp stop motion having, in combination, a plurality of drop wires, power-actuated mechanical devices effective to engage a drop wire upon the breaking of its supporting warp thread and to pull said wire forcibly downward, loom stopping mechanism, and a controlling member for said mechanism directly engaged by and 30 movable downwardly with a fallen drop wire.

In testimony whereof I have hereunto affixed my signature.

EPPA H. RYON.
